DESIGN FOR A BOTTLE

Joseph P. Sgueglia, New York, N. Y., assignor to Anthony Oechs & Company, Incorporated,
New York, N. Y., a corporation of New York

Application November 20, 1933. Serial No. 49,803

Term of patent 7 years

To all whom it may concern:

Be it known that I, JOSEPH P. SGUEGLIA, a citizen of the United States, residing in the city of New York, county of New York, and State of New York, have invented a new, original, and ornamental Design for a Bottle, of which the following is a specification, reference being had to the accompanying drawing, forming a part thereof.

Fig. 1 is a face view of a bottle embodying my design.

Fig. 2 is a side view of the same.

Fig. 3 is a plan view of the bottle, and

Fig. 4 is a sectional view on the plane of the line 4—4 of Fig. 2.

I claim:

The ornamental design for a bottle substantially as shown.

JOSEPH P. SGUEGLIA.
